UNITED STATES PATENT OFFICE.

WILHELM BRASE, OF BERLIN, GERMANY.

SEWING MACHINE.

Original application filed October 12, 1923, Serial No. 668,250. Divided and this application filed April 21, 1925. Serial No. 24,767.

To all whom it may concern:

Be it known that I, WILHELM BRASE, a citizen of the German Republic, residing at Berlin, Prussia, Germany, have invented 5 certain new and useful Improvements in Sewing Machines, of which the following is a specification.

This application is a division from the application Serial No. 668,250, filed Octo- 10 ber 12, 1923.

This invention relates to a jacquard device for automatically controlling the adjustment of the fabric feed or needle carrier frame, according to predetermined patterns 15 in embroidery sewing-machines.

With such machines, in order to reduce as much as possible the inertia of the parts to be displaced in the short period of time available and necessitating quick jerky ad- 20 justments, I provide, in accordance with this invention, a track or guide, which in itself is well-known in the sewing-machine art, and which I arrange in the jacquard control mechanism, so that it will actuate a 25 cam operated lever, whose longitudinal displacement is transmitted to the needle guide frame or fabric feed, while the adjustment of the track into inclined positions is ef- fected, according to predetermined pattern 30 under the control of a jacquard mechanism.

My invention is illustrated in the accompanying drawing in which similar reference characters denote corresponding parts and in which the same is shown in connection 35 with the needle guide frame, the application of my invention to a fabric feed being sub- stantially the same.

Fig. 1 is a somewhat diagrammatic view 40 of my device illustrating its cooperation with parts of an embroidery sewing-ma- chine and Fig. 2 is a section through the bearing of the track or guide.

n denotes the embroidery needle of a sewing-machine slidably guided in a rigid frame *a*, which at its rear is formed with a rack *b*. The latter rests on a stationary sharp edge or tooth *d*, and is held in position thereon by a roller provided on the end of a pin or finger *c* actuated by a pressure 45 spring *c'*. Capable of alternately engaging and disengaging the rack *b*, is a dog or tooth *r* projecting from the free end of one arm 50 of a double armed lever *f*, the other arm of

which is bifurcated, as at 22, engaging around a revolving cam *v*, whereby the lever *f* is constantly rocked in vertical direction around a pivot *s*. The latter is arranged on the free end of the vertical arm *t* of an angular lever fulcrumed at *w* in a stationary part of the machine and whose horizontal arm *g* has pivoted to it at *x* one end of a rod *h*. The other end of said rod is bifurcated, as at 2, and engages around a constantly revolving cam 3, whereby the rod is rocked on its pivot *x* in a vertical direction in a plane at a right angle to that of the lever *f*. This rod carries a roller *l*, that engages a circularly curved groove or track *i* formed in a block *i'*, which is pivoted centrally in the stationary frame of the machine, as at 4, (Fig. 2). From one end of said block, projects an arm 5, the free end of which is actuated by two oppositely acting springs *k* fastened to the frame of the machine and which have the tendency nor- mally to maintain the block *i'* in a central or normal position in which the roller *l* will be moved in the groove *i*, describing a circular path around the pivot *v* of the lever *h*, and consequently not displacing the latter longitudinally, so that in this case the angular lever *t*, *g* remains at rest and no motion is transmitted to the rack *b* or frame *a* by the dog or tooth *r*. Pivots connected at 6 and 7 to the ends of the block *i'*, are 55 fingers *m*, *m'*, which are vertically guided in stationary parts of the machine frame, as at *m*^a, and the upper ends of which are bent toward one another, leaving between them only a narrow slit *m*^b.

Suitably mounted in the machine frame, as at 8^a, above the bent ends of the fingers *m*, *m'*, is a shaft 8 carrying an eccentric or cam *u* adapted to actuate a plunger *o*, so as to reciprocate the latter vertically. Pivoted to the lower end of the plunger, is a rod *p* suitably guided, as at *p*^a, and carrying on its free end a roller *9*. A spring 10 connected to the plunger *o* has the ten- 100 dency to draw the plunger laterally and maintain it in contact with a pattern chain *g*, which is suitably mounted on and fed around a guide member 11. The pattern chain is composed of a plurality of differ- ently sized cam members or links *q'*, *q*², *q*³ 105 capable of actuating the plunger, so as to

bring it into different positions. In the present example, three positions are desired, and accordingly, the pattern members are of three different sizes. In the central or normal position shown by full lines in Fig. 1, the plunger is located centrally above the slit m^b between the ends of the fingers m , m' , and when actuated by the eccentric u will freely pass through said slit without having any effect on the track block i' , so that the latter maintains its central or neutral position at which there is no motion transmitted to the needle guide frame. When the plunger, by virtue of a correspondingly sized pattern link, is swung to one or the other side of its central position, either to the left or right, indicated by dotted lines, it will, when moved downwardly under the action of the eccentric u , be thrust against the corresponding finger m or m' , as a result of which the track block i' will be tilted against the action of the springs k around the pivot 4 into a slanting position relative to the normal, in which the circular path or track i of the roller l carried by the rod will be eccentric relative to the pivot x . In such position of the rack, the lever h will be caused, during its lateral swinging movements, while following the track i , to also and positively move longitudinally. This longitudinal movement will be transmitted to the angular lever g , t , thereby causing the dog r on disengaging the rack b from the stationary tooth d to move it either to the right or left, according to the direction into which the track block i' has been tilted.

The arrangement described has the advantage that when employing a corresponding pattern, the extent of movement imparted by the dog r to the rack b or frame a can be adjusted, so that the length and direction of the stitches can be changed in various ways. This can be accomplished by providing an adjustable eccentric or cam or a plurality of eccentrics of different eccentricity or cams of different sizes and by causing their corresponding plungers to be selectively controlled by the pattern chain g in the above described manner to act on corresponding fingers m , m' .

Another way of accomplishing this would be by providing the plunger with steps or making it of staggered thicknesses, so that the individual steps thereof will act on the corresponding fingers m , m' , depressing the same to different depths. In such case, of course, the pattern chain members will have to be of greater variation than in the first case, in order to effect graduated displacements of the plunger to the right or left to bring its different steps into range with the fingers m , m' . It is also possible to have the pivot x bear in a longitudinal slot of the lever h , in order to transmit a vari-

able movement to the tooth r through the constantly uniform movement of the rod h . There are, however, many other modifications possible to bring about variations of the length of stitches.

In case the track block i' cannot be maintained in a central or neutral position under the action of two springs, a single pull spring may be used to extend longitudinally of the arm 5.

What I claim is:—

1. In a sewing-machine, a needle guide carrying frame formed with a rack, a stationary knife edge on which said rack is displaceably supported, a constantly swinging dog capable of alternately engaging and disengaging said rack, and means for displacing said frame, including a constantly swinging lever operatively connected to said dog and an adjustable track in which said lever is positively guided and a jacquard mechanism controlling the adjustment of said track, so as to vary the movement of said lever and dog and consequently the stitches.

2. In a sewing-machine, a needle guide carrying frame formed with a rack, a stationary knife edge on which said frame is displaceably supported, a constantly swinging dog capable of alternately engaging and disengaging said rack, a guide member formed with a circularly curved track or guide groove, a constantly swinging lever positively guided in said groove and a jacquard controlled reciprocating member capable of tilting the track into different positions, so as to vary the movements of said lever and dog and consequently the stitches.

3. In a sewing machine, a needle guide carrying frame, a stationary means for displaceably supporting said frame, and means for displacing said frame to vary the stitches, said means including a constantly swinging member, a curved guide in which said member is displaceably guided, and a jacquard controlled plunger capable of operatively engaging either side of said guide and tilt the latter so as to displace said member therein and consequently vary the displacement of said frame.

4. In a sewing machine, a needle guide carrying frame, a stationary means for displaceably supporting said frame and means for displacing said frame to vary the stitches, said means including a constantly swinging member, a curved guide in which said member is displaceably guided and a jacquard controlled cam operated plunger capable of operatively engaging either side of said guide and tilt the latter so as to displace said member therein and consequently vary the displacement of said frame.

5. In a sewing machine, a needle guide

carrying frame, a stationary means for displaceably supporting said frame, and means for displacing said frame to vary the stitches, said means including a constantly swinging lever mechanism, a spring actuated curved guide in which said lever mechanism is adjustably guided and a

jacquard controlled cam operated plunger capable of operatively engaging either side of said guide and tilt the latter so as to 10 adjust said lever mechanism and thereby vary the displacement of said frame.

In testimony whereof I affix my signature.

WILHELM BRASE.
